ANTENNA POINTING APPARATUS

Kenneth E. Schreiner, Boston, Mass., assignor,
by mesne assignments, to the United States of
America as represented by the Secretary of War

Application October 3, 1945, Serial No. 620,136

6 Claims. (Cl. 343—7)

1

This invention relates to highly directive antennas and more particularly to apparatus for causing an antenna to point in elevation at a selected target.

In many applications of radio object-locating apparatus it is desirable to point the antenna in elevation at a selected target. Antennas may be of two general types as classified by their elevation beam angles, narrow or broad. In general antennas having narrow elevation beam angles must be pointed directly at the selected target. This has previously been done by circuits utilizing signal strength of the echo returned by the target. The so-called cosecant squared ($\csc^2$) antenna is so designed that targets at all elevation angles produce substantially equal return signal intensities. However, such an antenna does not normally possess uniform azimuth resolution characteristics at all elevation angles. In applications wherein optimum azimuth resolution is desired elevation pointing is, therefore, desired. It will be obvious that other means than signal strength must be employed to properly point such an antenna because of its elevation characteristic mentioned above.

It is an object of the present invention, therefore, to provide a circuit for pointing an antenna in elevation.

For a better understanding of the invention, together with other and further objects thereof, reference is had to the following description taken in connection with the accompanying drawing which illustrates in block and diagrammatic form the preferred embodiment of the present invention.

Referring now to the drawing, there is shown the preferred embodiment of the present invention which comprises a control box 11 having voltages on leads 12, 13 and 14, respectively designated V_A , V_G , and V_{REF} . The control box 11 is preferably of the type disclosed and claimed in the copending application of Byron L. Havens and John J. Lentz, for Electrical Apparatus, Serial No. 620,135, filed October 3, 1945, but it may be any source providing an alternating voltage V_A , which is proportional to the altitude of the aircraft or of the antenna, an alternating voltage V_G , which is proportional to ground range to the target, and a reference voltage V_{REF} which is in phase with V_G . The voltage V_A on lead 12 is passed through a phase shifting device 15 which produces sufficient phase shift in V_A so that V_A and V_G are in 180° phase opposition. In the control box 11 as disclosed in the cited copending application V_A and V_G are in quadrature, and de-

2

vice 15 then produces 90° phase shift. From the phase shifter 15, V_A is impressed across a capacitor 16 and resistor 17 to ground. The voltage V_G on lead 13 is connected across a potentiometer 21. The potentiometer 21 is so constructed that the resistance to ground measured from the tap 22 when plotted as a function of displacement of the tap 22 is a tangent curve. The potentiometer 21 may alternatively be linear and so loaded, e. g. by resistor 19, that the output voltage will be substantially equal to a constant multiplied by the tangent of the angle by which the antenna 23 deviates from a predetermined position. The antenna 23 of the associated radio object-locating equipment is mechanically connected to the tap 22 in such a manner that the voltage on tap 22 will be proportional to the voltage, V_G , multiplied by the tangent of the angle of depression of the antenna 23. Tap 22 is connected through a capacitor 24 and a resistor 25 to ground. The resistances of resistors 17 and 25 should be of equal magnitude. A resistor 26 and a resistor 27 are connected in series between the junction of capacitor 16 and resistor 17 and the junction of capacitor 24 and resistor 25. The resistances of resistors 26 and 27 should be equal. The junction of resistors 26 and 27 is connected to an amplifier 31 which in turn connects to a phase splitter 32. The phase splitter 32 may be any device capable of producing a push-pull output signal from a single-ended input signal. The push-pull output from the phase splitter 32 is connected to control grids 33 and 34 of multigrid tubes 35 and 36. Anodes 37 and 38 of tubes 35 and 36 are returned to a suitable source of positive potential. The reference voltage V_{REF} on line 14 which is in phase with V_G is connected to a second grid 41 and 42, respectively, of tubes 35 and 36. A coil 43 of a differential relay denoted generally by 44 connects between cathodes 45 and 46 of tubes 35 and 36. A center tap on coil 43 is connected to ground. Fixed contact 51, together with movable contacts 52 and 53 provide a single-pole double-throw switch which is connected to the motor which moves the antenna 23 in elevation. The elevation motor 70 and its associated power source 72 are connected as shown.

In the operation of the antenna elevation pointing circuit shown in the accompanying drawing an alternating voltage from control box 11 of amplitude V_A , proportional to the altitude of the aircraft, is properly shifted in phase and impressed across resistor 17. At the same time an alternating voltage, V_G , having an amplitude proportional to the ground range of the target, i. e.

range measured from a point beneath the aircraft to the target and supplied by control box 11 is applied across potentiometer 21. The voltage at the tap 22 is the product resulting from a multiplication of V_G and the tangent of the present angle of depression of the antenna 23 which is mechanically connected to tap 22. The voltage at tap 22 is applied across resistor 25. The relative phase of the signals across resistors 17 and 25 are indicated by waveforms 61 and 62. From an elementary consideration it will be seen that if the amplitude of the signals across resistors 17 and 25 are equal no voltage will exist at the input to amplifier 31. This condition is the desired condition, and the antenna 23 will point toward the target. However, if the antenna does not point toward the target, a signal will appear at the input to amplifier 31 and will have a waveform such as 63 or 64, depending upon whether the antenna points too high or too low in elevation. The signal at the input to amplifier 31 is amplified therein and passed through the phase splitter 32 with resulting output waveforms 65 and 66 or 67 and 68, depending upon whether the input to amplifier 31 was as 63 or 64. The reference voltage V_{REF} on lead 14 for control box 11 will have a waveform and phase indicated by 71. If signals having phases indicated by 65 and 66 are present at grids 33 and 34, it will be seen that tube 35 will conduct more heavily than will tube 36 with the result that contacts 51 and 52 will make connection and the elevation motor will move the antenna up in elevation to reduce the signal at the input to amplifier 31 to zero. In an exactly similar manner it can be shown how the relay 44 will be operated to move the antenna down in elevation when the signal at the input to amplifier 31 is as shown by waveform 64.

While there has been described what is at present considered the preferred embodiment of the invention, it will be obvious to those skilled in the art that various changes and modifications may be made therein without departing from the invention.

What is claimed is:

1. An electrical apparatus associated with radio object-locating equipment for pointing a rotatable antenna in elevation at a target, said apparatus comprising a signal source providing a pair of sinusoidal voltages proportional respectively to the altitude of the antenna above the target, and to ground range to the target, said source also providing a reference voltage, potentiometer means connected to said signal source and energized by said ground range voltage, said potentiometer means having a movable tap thereon mechanically connected to the antenna, phase shifter means connected to said signal source and providing from said altitude voltage an output voltage substantially out of phase with the voltage on said tap, resistive adding means connected to said phase shifter means and tap for providing a difference voltage proportional to the difference in magnitudes of the voltage on said tap and said output voltage, and comparator means operatively connected to said adding means and signal source for receiving said difference and reference voltages and being constructed and arranged and connected to said antenna for causing the antenna to rotate in such a direction as to reduce said difference voltage to zero.

2. In antenna pointing apparatus of the character disclosed for use on aircraft for maintaining an antenna pointing at a target, in combination, movable antenna means including an

antenna adapted to be selectively rotated in two opposite directions about a normally horizontal axis, means for obtaining a plurality of alternating voltage signals of the same frequency including a reference signal of predetermined amplitude, a ground range signal in phase with said reference signal and having an amplitude proportional to the ground range of the target, and an altitude signal having a phase substantially 180 degrees out of phase with said ground range signal, means energized by said ground range signal and operatively connected to said antenna for providing an output signal substantially proportional to ground range times the tangent of the angle of depression of the antenna from the true horizontal, means having said output signal and altitude signal applied thereto for providing a difference signal having an amplitude proportional to the difference between the output and altitude signals and a phase determined by which of said last named signals is the larger, and means operatively connected to said last named means, to said generator means, and to said antenna means for utilizing said difference signal and reference signal to rotate said antenna up and down selectively in accordance with the phase relation of said difference signal with respect to said reference signal.

3. In antenna pointing apparatus of the character disclosed for use on aircraft for maintaining an antenna pointing at a target, in combination, movable antenna means including an antenna adapted to be selectively rotated in two opposite directions about a normally horizontal axis, generating means for obtaining three alternating voltage signals of the same frequency including a reference signal having a predetermined amplitude, a ground range signal in phase with said reference signal and having an amplitude proportional to the ground range of the target, and an altitude signal having an amplitude proportional to the altitude of the aircraft and a phase difference of substantially ninety degrees with respect to said reference signal, phase shifter means connected to said generator means and having said altitude signal applied thereto for providing a first output signal substantially 180 degrees out of phase with said ground range signal, potentiometer means energized by said ground range signal and operatively connected to said antenna for providing a second output signal substantially proportional to ground range times the tangent of the angle of depression of the antenna from the true horizontal, adding network means having said first and second output signals applied thereto for providing a difference signal, and means operatively connected to said adding network means, to said generator means, and to said antenna means for utilizing said difference signal and reference signal to rotate said antenna up and down selectively in accordance with the phase relation of said difference signal with respect to said reference signal.

4. In antenna pointing apparatus of the character disclosed for use on aircraft for maintaining an antenna pointing at a target, in combination, movable antenna means including an antenna adapted to be selectively rotated in two opposite directions about a normally horizontal axis, means for obtaining a plurality of alternating voltage signals of the same frequency including a reference signal of predetermined amplitude, a ground range signal in phase with said reference signal and having an amplitude proportional to the ground range of the target, and

an altitude signal having a phase substantially 180 degrees out of phase with said ground range signal, means energized by said ground range signal and operatively connected to said antenna for providing an output signal substantially proportional to ground range times the tangent of the angle of depression of the antenna from the true horizontal, adding network means having said output signal and altitude signal applied thereto for providing a difference signal, phase splitter means operatively connected to said network means and energized therefrom for providing from said difference signal two additional difference signals of opposite phase and substantially equal amplitude, push-pull phase discriminator means energized by said two additional difference signals and having said reference signal applied thereto, and means energized from said phase discriminator means and operatively connected to said antenna for rotating said antenna.

5. In antenna pointing apparatus of the character disclosed for use on aircraft for maintaining an antenna pointing at a target, in combination, relay controlled movable antenna means including an antenna adapted to rotate in two opposite directions about a normally horizontal axis selectively in accordance with the contact position of the relay, generating means for obtaining three alternating voltage signals of the same frequency, including a reference signal having a predetermined amplitude, a ground range signal in phase with said reference signal and having an amplitude proportional to the ground range of the target, and an altitude signal having an amplitude proportional to the altitude of the aircraft and a phase difference of substantially ninety degrees with respect to said reference signal, phase shifter means connected to said generator means and having said altitude signal applied thereto for providing a first output signal substantially 180 degrees out of phase with said ground range signal, potentiometer means energized by said ground range signal and operatively connected to said antenna for providing a second output signal substantially proportional to ground range times the tangent of the angle of depression of the antenna from the true horizontal, adding network means having said first and second output signals applied thereto for providing a difference signal, phase splitter means operatively connected to said network means and energized therefrom for providing from said difference signal two additional difference signals of opposite phase and substantially equal amplitude, and push-pull phase discriminator means energized by said two additional difference signals and having said reference signal applied thereto, said phase discriminator means having said antenna control relay connected thereto and energized therefrom for causing said relay to as-

60

sume two contact positions selectively in accordance with the phase relation between the reference signal and the difference signal.

6. In antenna pointing apparatus of the character disclosed for use on aircraft for maintaining an antenna pointing at a target, in combination, relay controlled movable antenna means including an antenna adapted to rotate in two opposite directions about a normally horizontal axis selectively in accordance with the contact position of the relay, generating means for obtaining three alternating voltage signals of the same frequency, including a reference signal having a predetermined amplitude, a ground range signal in phase with said reference signal and having an amplitude proportional to the ground range of the target, and an altitude signal having an amplitude proportional to the altitude of the aircraft and a phase difference of substantially ninety degrees with respect to said reference signal, phase shifter means connected to said generator means and having said altitude signal applied thereto for providing a first output signal substantially 180 degrees out of phase with said ground range signal, potentiometer means energized by said ground range signal and operatively connected to said antenna for providing a second output signal substantially proportional to ground range times the tangent of the angle of depression of the antenna from the true horizontal, adding network means having said first and second output signals applied thereto for providing a difference signal, phase splitter means operatively connected to said network means and energized therefrom for providing from said difference signal two additional difference signals of opposite phase and substantially equal amplitude, electron discharge tube means including a pair of electron discharge tubes each having two grids, circuit means applying said two additional difference signals on one grid of each of said two tubes respectively, circuit means applying said reference signal in phase on the remaining grid of both of said tubes, said electron discharge tube means being connected to said relay for controlling the contact position thereof and causing said antenna to rotate in two directions selectively in accordance with the phase relation between the reference signal and the difference signal.
